FIG. 3.

UNITED STATES PATENT OFFICE

2,669,185

HYDRAULIC IMPELLER OR PUMP

Charles Edward Tallis, Handsworth, Birmingham, England, assignor to Birmingham Tool & Gauge Company Limited, Handsworth, England

Original application August 20, 1951, Serial No. 242,763. Divided and this application March 6, 1953, Serial No. 340,804

6 Claims. (Cl. 103—38)

1

This application is a division of my application Serial No. 242,763 filed August 20, 1951, now Patent No. 2,657,046, for Automatic Feed Mechanism for Power Presses and Like Machines, and comprises improvements in or relating to hydraulic impellers or pumps and has for its object to provide such an impeller or pump in which a sufficient volume of fluid is displaced in one revolution thereof to effect a controlled movement on an associated hydraulic linkage coupled thereto, whilst at the same time on each revolution of the pump an over induction of fluid in an associated hydraulic linkage is effected half way through its cycle and compressed at the completion of the cycle.

Referring to the accompanying drawings—

Figure 1 is a cross sectional elevation of a pump or impeller according to the present invention.

Figure 2 is a view taken on the line 11—11 of Figure 1, i. e. an end view of the impeller with the cover removed.

Figure 3 is a view of the other end of the impeller, and

Figure 4 is a detail sectional view on an enlarged scale of one of the impeller plungers showing the automatic replenishing valve mechanism therein.

In carrying the present invention into practice as shown upon the accompanying drawings, the impeller comprises two pairs of plungers 60, 60 and 61, 61 operating in bushes 62 in the wall 63 of the impeller housing, the pair of plungers 60, 60 which operate together enter a chamber 64 communicating with the pipe 16, whilst in a similar manner the pair of plungers 61, 61 enter a chamber 65 communicating with the pipe 17, the ends of the plungers remote from said chamber are each provided with rollers 66 for contact with pivoted members 67, 68 which are pivoted to support members or blocks 69, 70. These pivoted members 67, 68 each carry universally pivoted thereon shoes 71 bearing against the face of a swash plate or face cam 72 rotatably mounted in the cover 73 of the impeller housing and driven in any suitable manner.

The blocks 69, 70 have a screw threaded engagement with the threaded portions 74, 75 of the vertical shaft 76 rotatably mounted in the impeller housing and having secured to its upper end the control knob 20. The threaded portions 74, 75 of this shaft are of opposite hand so that on rotation of the shaft the blocks 69, 70 are either moved apart or towards one another. Thus by manipulating the knob 20 the shoes 71 are either moved towards the centre of the face cam 72 to reduce the stroke of the plungers 60, 60 and 61, 61 so that the minimum of oil movement takes place along the pipes 16, 17 or said shoes 71 may be adjusted towards the periphery of the cam or swash plate 72 to obtain maximum

2

stroke of the plungers and consequent maximum movement of fluid along the pipes 16, 17 to operate an associated hydraulic linkage.

The ends of the plungers 60, 60, 61, 61 within the chambers 64, 65 respectively are bored at 77 (Figure 4) to receive compression springs 78 for abutment therein, the outer ends of the springs 78 abutting the wall 63 of the impeller housing in order to maintain the rollers 66 at 10 the other ends of the pistons in contact with the pivoted members 67, 68.

The housing of the pump containing the swash plate 72 and associated mechanism serves as a reservoir for oil at atmospheric pressure for the purpose of replenishing the two lines of oil under pressure between the impeller and an associated hydraulic linkage, in order to make good any loss. For this purpose communication is effected between the housing of the pump and the chambers 64, 65 by means of automatic valves contained in at least one plunger 60 or 61 of each pair.

The automatic valve of one of the plungers 60 is shown in Figure 4 from which it will be seen that the roller 66 is carried by a forked head 80 having a shank 81 fitting in a bore 82 in the other end of the plunger 60, said shank having an axial through bore 83 therein.

Located in the bore 82 for limited sliding movement between the inner end of the shank 81 and the annular shoulder 84 in the plunger 60 is a valve member 85 the full diameter portion 86 of which is an oil tight sliding fit in the bore 82 and when in the position shown closes the inner end 30 of the bore 83 in the shank 81 from the bore 77 and hence from communication with the chamber 64, the valve member 85 being urged to this position by pressure of oil thereon from said chamber.

40 However, upon a fall in oil pressure in the chamber 64 and as the piston 60 effects an outward suction stroke therein the suction on the valve member 85 moves it towards and against the annular shoulder 84 enabling oil to be inducted from the impeller housing through the bore 83 in the shank 81 and via the reduced portion 87 of the valve member 85 (which then registers with the annular groove 88 in the plunger) to the bore 77 and from thence into the chamber 64.

55 Inductance of oil through the above described automatic non-return valve in the plunger 60 is promoted by virtue of the fact that due to the action of the swash plate 72 the plungers 60, 60, 61, 61 are not reciprocated at a constant speed. Thus after a quarter of the way through a feeding cycle when the swash plate has rotated through 90° the plungers 61 advancing into the chamber 63 to impel oil along the pipe 17 to an associated hydraulic linkage, but the plunger 60

receding from the chamber 64 to assist and accommodate return movement of oil from the pipe 16 have a slightly greater extent of movement creating a partial vacuum in the chamber 64 to assist inductance of oil through the plunger 60 that is fitted with the automatic valve.

Halfway through the cycle the extent of movement of the plungers 60, 60 equals that of the plungers 61, 61 and three-quarters of the way through the cycle a similar accelerated movement of the plungers 61, 61 receding from the chamber 65 takes place to create a partial vacuum in the latter for promoting the desired oil inductance through an automatic valve in one of the plungers 61 identical with that described and shown in one of the plungers 60.

The arrangement of the annular groove 88 in relation to the reduced portion 87 of the valve member 85 is such that the passage of oil is only permitted when the valve member is fully against the shoulder 84 otherwise too great a quantity of oil would tend to be inducted through the plunger.

I claim:

1. A hydraulic impeller or pump comprising a body part; a swash plate rotatably mounted for driven rotation in said body part; at least one movable support member carried by said body part and adjustable radially with respect to the swash plate; at least one member pivoted to said support member and extending adjacent the face of said swash plate; a shoe carried by said pivoted member and bearing against the face of said swash plate; at least one hydraulic fluid chamber provided on said body part; and at least one plunger having one end slidable in said chamber whilst the other end abuts said pivoted member, the arrangement being that on adjustment of said support member the shoe of the pivoted member is moved relative to the axis of the swash plate thus varying the degree of pivotal movement of the pivoted member and the point of abutment therewith of the plunger with consequent variation in stroke of the latter.

2. A hydraulic impeller or pump comprising a casing; a swash plate rotatably mounted in said casing; at least one movable support member carried by said casing; screw means carried by said casing and arranged to act on said support member for adjusting the latter radially with respect to the swash plate; at least one member pivoted to said support member and extending adjacent the face of said swash plate; a shoe carried by said pivoted member and bearing against the face of said swash plate; at least one hydraulic fluid chamber provided on said casing; and at least one plunger having one end slidable in said chamber whilst the other end abuts said pivoted member, the arrangement being that on adjustment of said support member the shoe of the pivoted member is moved relative to the axis of the swash plate thus varying the degree of pivotal movement of the pivoted member and the point of abutment therewith of the plunger with consequent variation in stroke of the latter.

3. A hydraulic impeller or pump according to claim 2 wherein the casing of the impeller is adapted to serve as a reservoir for hydraulic fluid whilst at least one plunger to the hydraulic fluid chamber is provided with a bore containing an automatic non-return valve for effecting inductance of fluid from the casing to the chamber in order to replenish the latter on a fall in hydraulic fluid pressure therein due to fluid loss.

4. A hydraulic impeller or pump according to

claim 3 wherein the automatic non-return valve comprises a valve member having limited movement in a bore in the plunger and adapted to be normally urged by pressure of fluid from the chamber to a position in said bore to prevent passage of fluid therethrough but adapted on a fall in fluid pressure in said chamber to move to a position to permit inductance of fluid through the bore in said plunger into the chamber.

5. A hydraulic impeller or pump comprising a casing; a swash plate mounted for driven rotation in said casing; a shaft rotatably mounted in said casing and disposed at right angles to the axis of said swash plate and having two threaded portions thereon of opposite hand to one another; a pair of support members threaded one each on said threaded portions of said shaft so that on rotation of the latter they move towards or away from one another and the axis of said swash plate; a pair of members pivoted one each to said support members and both extending adjacent the face of said swash plate; a pair of shoes carried one each by said pivoted members and bearing against the face of said swash plate; a pair of hydraulic fluid chambers mounted on said casing, and adapted to be connected one each to the two hydraulic fluid lines; at least one pair of plungers having corresponding ends slideable one each in said chambers whilst the other ends of said plungers abut one each against said pivoted members so that the plungers are arranged to reciprocate in opposite directions, the arrangement being that on rotation of the shaft the support members are moved to in turn adjust the position of the shoes of the pivoted members against the face of the swash plate relative to the axis of the latter thus varying the degree of pivotal movement of the pivoted members and the points of abutment therewith of their corresponding plungers with consequent variation in the stroke of the latter.

6. A hydraulic impeller or pump according to claim 5 wherein the casing of the impeller is adapted to serve as a reservoir for hydraulic fluid whilst at least one plunger to each hydraulic fluid chamber is provided with a bore containing an automatic non-return valve for effecting inductance of fluid from the casing to the chambers in order to replenish the latter on a fall in hydraulic fluid pressure therein due to fluid loss, the arrangement being that the swash plate is adapted to actuate the plungers through the pivoted members so that the reciprocating movement of the plungers is not at a constant speed to one another so that at stages during the reciprocatory cycle one plunger recedes from its chamber to a greater extent than the entering movement of the other plunger into its chamber in order to create a condition of partial vacuum in that chamber from which the plunger is receding to promote fluid inductance past the automatic valve in said plunger.
